UNITED STATES PATENT OFFICE.

ADOLPH MOHRBACHER, OF DENVER, COLORADO.

UNIVERSAL FENCE-WIRE ATTACHMENT FOR CONCRETE POSTS.

Application filed February 26, 1921. Serial No. 448,121.

To all whom it may concern:

Be it known that I, ADOLPH MOHRBACHER, a citizen of the United States, residing at Denver, in the county of Denver and State 5 of Colorado, have invented certain new and useful Improvements in Universal Fence-Wire Attachments for Concrete Posts; and I hereby declare that the following is a full, clear, and exact description thereof, reference being had to the accompanying drawings, which form part of the specification.

My invention relates to fence-posts, and more especially to those formed in the solid from concrete, cement or other suitable material, and its object is to provide fastenings whereby the running wires of a fence may be fastened thereto.

Another object is to provide a frame work of wire consisting of vertical wires for reinforcing, together with two or more sets of cross wires extending beyond the exterior of the post, the wires of each set being twisted together after receiving there between, a running wire of the fence.

Still another object is to allow the vertical wires to extend beyond the top of the post. This construction permits of attaching an ornamental top, as is generally used on a gate post and often upon all the posts 30 where the fence encircles a house or garden. These protruding wires also permit the fastening of a top wire. Such a wire is often a barbed wire where the body wires are smooth.

Another object is for attaching guy wires where, as at a corner or on sloping ground, or where the fence follows a curved line, it becomes necessary to guy the fence posts to offset the strain of the running wires.

With the above as some of my objects my invention consists in a novel combination, construction and arrangement of the parts thereof to be hereinafter more fully described and claimed.

In the accompanying drawings Fig. 1 is a view in front elevation illustrating one of my posts with three running wires of the fence. Fig. 2 is a vertical sectional view on the line $x-x$ of Fig. 1 showing the simple 50 construction of my wire frame. Fig. 3 shows a modification in cross section showing the frame extending above the top of the post and an ornamental cap ready to be mounted thereon.

Fig. 4 is a modification showing a portion 55 of the top of a post with a running barbed wire strand in place also a guy wire.

Fig. 5 shows my wire reinforcing frame as it appears while being unrolled.

Fig. 6 represents a cross section illustrating how my wire frame B is bent to fulfill the requirements of a corner post.

Referring more particularly to the drawings, A designates concrete, cement or other suitable material which may be molded 65 while in a plastic state and permitted to set and harden. B denotes the reinforcing wire frame consisting of uprights or vertical wires b which have cross wires b' suitably seamed to said uprights secured by welding, 70 soldering or the like. C shows a smooth running wire held securely by the entwined wires b'. In the modification shown in Figs. 3 and 4 the vertical wires b² are shown projecting above the top of the post 75 A. These wires b² are suitable for mounting thereon an ornamental cap D for beautifying and also for protecting the top of the post from the weather. In Fig. 4 I have shown how a barbed wire E may be run over 80 the top of my post and be secured thereto by vertical wires b² and how these vertical wires b² provide grips for a guy wire F.

My construction of the wire which reinforces and provides tie wires is such that it 85 may be made in long strips and rolled up and cut off as it is required and placed in the liquid concrete before it hardens in the fence post mould.

It will be seen that my reinforcing frame 90 of wire is flat and will permit of making the posts narrow on the side where the line wires are attached, and with considerable depth to withstand the line wire tension. It is also apparent that with these narrow 95 posts they take up much less room and many more may be carried upon one load when laying-out the line of fence.

It will also be apparent that my fastening devices are such that the tie wires may be 100 readily united if it becomes necessary to move a post or relocate the line of fence.

I prefer to make my wire frame of vertical wire members, cross wire members or tie wires of a less diameter rigidly attached 105 thereto. The tie wires placed in pairs, one wire in front and one wire in back of the said vertical members and spaced horizon-

tally to receive and entwine a running fence wire. I do not however, wish to limit myself to the number of vertical members and tie wire members.

5 In the manufacture of my post as shown in Figs. 3 and 4 I prefer to bend the vertical wires for the purpose of placing the wire frame in the mould. I bend the vertical wires at right angles so that the bent portion will be upon the top of the post when formed and may then be easily straightened again to the original vertical position.

10 In the manufacture of my posts I find it is desirable to have the wire frame made in a continuous roll and cutting off sections as desired. This feature I consider of great 15 advantage as I can transport the wire in

rolls to the point at which the moulds are to be set up.

Having fully described my invention what 20 I desire to claim and secure by Letters Patent is:—

A panel-shaped post comprising two vertical reinforcing members serving as means for securing the cross wire members said 25 vertical members extending above the post body for attachment thereto of post caps or running wires, and a plurality of cross wire members secured at right angles to said vertical members and spaced apart in different horizontal planes.

In testimony that I claim the foregoing as my own, I affix my signature.

ADOLPH MOHRBACHER.
